UNITED STATES PATENT OFFICE.

WILLIAM T. CHAMBERLAIN, OF NORWICH, CONNECTICUT, ASSIGNOR TO DE YOUNG & BROTHER, OF PHILADELPHIA, PENNSYLVANIA.

DESIGN FOR AN ORNAMENTAL CHAIN.

Specification forming part of Design No. 11,211, dated May 27, 1879; application filed April 16, 1879.
[Term of patent 7 years.]

To all whom it may concern:

Be it known that I, WILLIAM T. CHAMBERLAIN, of Norwich, in the county of New London and State of Connecticut, have originated and designed a Pattern for Watch and other Wearing Chains, of which the following is a full, clear, and exact description, reference being had to the accompanying illustration or drawing, making part of this specification.

My design consists of a watch or other wearing chain, the links A of which represent cars. I do not confine myself to any particular style or character, but will use cars of any plan, form, or outline.

What I claim as my invention is—

The design for an ornamental chain, consisting of a representation of a train of cars, substantially as illustrated and described.

In testimony whereof I hereunto sign my name in presence of two subscribing witnesses.

WILLIAM T. CHAMBERLAIN.

Witnesses:

EDWIN ALLEN,
JOHN KENDALL.
